UNITED STATES PATENT OFFICE.

CARL WEBER, OF HILTON, NEBRASKA.

CIRCUIT CLOSER FOR HOLD-UP ALARMS.

Application filed May 27, 1926. Serial No. 111,981.

The main object of this invention is to provide a burglar alarm which is operated by the foot so that the signal may be given unobservedly. This device is applicable particularly to banks, counting rooms, and the like.

The above and other objects will become apparent in the description below, in which characters of reference refer to like-named parts in the drawing.

Referring briefly to the drawing, Figure 1 is an elevational view, illustrating the outline of a counting room, showing the invention as applied.

Figure 2 is a sectional elevational view of the burglar alarm switch.

Figure 3 is a sectional elevational view taken on line 3—3 of Figure 2.

Figure 4 is a top plan view of Figure 2.

Referring in detail to the drawing, the numeral 10 indicates the bench of a counting room which is enclosed by a wall in which a window frame 11 is formed. This window is provided with a lattice frame 12 as is usual in all counting houses. Along the frame of the window on one side thereof, a plurality of push button units 13 and 14 are mounted so that the teller in the caged room may give a signal with the hands when the latter are free to do so. The retaining wall indicated by the numeral 15 of the building has a gong unit 16 attached to its exterior face. The push button units 13 and 14 are connected in parallel circuit with the gong and are energized thru some source of energy not shown. The lead wires between the push buttons and gong are mounted in a conduit 17. An additional conduit 18 extends downwardly from the gong to a position beneath the floor. At conveniently accessible positions in the floor box-like structures consisting of side walls 19 and 20 and a lowered bottom 21 are formed. This structure provides a box open at the top whose open end is covered by a platform 22 which has a hinge 23 secured to it. The free end of the platform has a pair of downwardly extending studs 24 which are guided into slots formed in a bracket 25, the latter being mounted on the wall 19 of the box-like structure. Between the bottom of the platform 22 and the bracket, springs 26 are mounted on the studs 24 and are adapted to seat upon said brackets and raise the platform to a position in which the platform

aligns itself with the floor 27 of the counting room. Centrally of the platform, a square sleeve 28 extends downwardly from said platform. This sleeve has a square socket therein in which a square shank 29 is slidably mounted. The shank has a pin 30 thereon which is engaged and registers in a vertical slot 31 formed in the sleeve, the said slot limiting the sliding movement of the shank 29. The lower end of the shank 60 has a bifurcated end 32 in which a pin 33 is mounted. An obtuse angled bell crank 34 is pivoted intermediate its length on the pin 33. One end of this bell crank has a vertical extending projection 35 which lies 65 in contact with and engages the lower surface of the platform 28, is being noted that the bifurcated end 32 of the shank 29 for operativeness must always lie in contact with a rigid surface such as the bottom 21. The 70 opposite arm 35 of the bell crank rests upon a horizontally extending finger 36 which has above it an additional finger 37 having a curved end, the edges of the fingers overlapping slightly and normally separated 75 by a gap 38. The fingers are rigidly mounted on the wall 20 of the box-like structure and have terminals 39 thereon to which lead wires connecting the gong 16 and the fingers are attached.

This burglar alarm may be operated by either the hands or the feet. Where the hands can be used, the push buttons 13 and 14 may be depressed to close the circuit thru the gong 16 so that the latter will give an 80 audible alarm. Were the feet to be used, the latter may rest on the floor near the platform 22. When the feet rest upon this platform and are pressed downwardly the platform is pivotally rotated, and the bell crank 85 34, which has one end in contact with the free end of the platform 22, is rotated downwardly. This causes the opposite arm 35 of the bell crank 34 to be lifted and thru this lifting, the lower finger 36 is bent upwardly, closing the gap 38 between the fingers 36 and 37, which causes both fingers to 90 mutually contact and close a circuit thru the gong 16, giving an audible alarm. The fingers are mounted in series in an electrical 95 circuit and form the circuit closer of the device. Further movement of the arm 34 downwardly causes the finger 36 to be fixed arcuately and the portions at the ends of the fingers 36 and 37 which overlap, trip the end 100 105 110

of the fingers 36 and contact with the opposite surface of the extremity of the finger 37 and when pressure on the platform is made, the fingers are in permanent mutual contact only as long as the platform remains depressed, and thereby give an alarm thru the gong 16. The lowermost finger 36 is deformed at its extreme end to provide a channel in which the upturned end of the arm 35 of the lever is engaged releasably when said arm is lifted. In order for this apparatus to operate, it is necessary that the bifurcated end 32 which supports the bell crank 34 rests upon the surface of the bottom 21. This bottom may not always have the same dimensions, being either a greater or lesser distance from the surface of the platform 22. To permit adjustment to compensate for this variation in dimension, the 20 shank, the bifurcated end 32, and the bell crank are made a floating unit slideable in the sleeve 28 so that when the platform is being lowered into position over the open end of the box-like structure, the shank and bell 25 crank unit will fall of its own volition to a position where it will finally rest on the bottom of the box-like structure.

It is to be noted that certain changes in form and construction may be made without departing from the spirit and scope of the 30 invention.

I claim:—

1. In an alarm, a switch comprising a box-like structure encased in a floor, a pair of resilient fingers in said box-like structure, a hinged platform covering said box-like structure, means in said box-like structure engaging the platform and fingers for closing the circuit thru said fingers upon depression of the platform comprising a bell crank, 40 said bell crank being attached to the platform and resting upon the bottom of the box-like structure, a deformed portion on one finger engaged by said bell crank, said bell crank being adapted to flex one of said fingers to lift the latter into contact with the opposite finger, and slidable means securing the bell crank to the platform allowing said bell crank support to rest upon the bottom of the box-like structure.

45

2. In an alarm, a switch comprising a box-like structure encased in a floor, a pair of resilient fingers in said box-like structure, a hinged platform covering said box-like structure, means in said box-like structure engaging the platform and fingers for closing the circuit thru said fingers upon depression of the platform comprising a bell crank, 50 said bell crank being attached to the platform and resting upon the bottom of the box-like structure, said bell crank being adapted to flex one of said fingers to trip the latter into permanent contact with the opposite finger, slidable means securing the bell crank to the platform allowing said bell crank support to rest upon the bottom of the box-like structure.

55

2. In an alarm, a switch comprising a box-like structure encased in a floor, a pair of resilient fingers in said box-like structure, a hinged platform covering said box-like structure, means in said box-like structure engaging the platform and fingers for closing the circuit thru said fingers upon depression of the platform comprising a bell crank, 60 said bell crank being attached to the platform and resting upon the bottom of the box-like structure, said bell crank being adapted to flex one of said fingers to trip the latter into permanent contact with the opposite finger, slidable means securing the bell crank to the platform allowing said bell crank support to rest upon the bottom of the box-like structure comprising a square sleeve mounted on the bottom of said platform in said box-like structure, a shank slideable in said sleeve, said sleeve having a slot therein, a 65 bifurcated end on said shank receiving the bell crank, and a pin on said shank rigid in said slot permitting vertical movement of the bell crank and the shank.

70 In testimony whereof I affix my signature.

CARL WEBER.
